UNITED STATES PATENT OFFICE.

WILLIAM E. SPARKS, OF NEW HAVEN, CONNECTICUT, ASSIGNOR TO
SARGENT & CO., OF SAME PLACE.

IMPROVEMENT IN DOOR-BELLS.

Specification forming part of Letters Patent No. 152,925, dated July 14, 1874; application filed
March 26, 1874.

To all whom it may concern:

Be it known that I, WILLIAM E. SPARKS, of New Haven, in the county of New Haven and State of Connecticut, have invented a new Improvement in Door-Bells; and I do hereby declare the following, when taken in connection with the accompanying drawings and the letters of reference marked thereon, to be a full, clear, and exact description of the same, and which said drawings constitute part of this specification, and represent, in—

Figures 1 and 2, sectional views of the invention.

This invention relates to an improvement in that class of gong-bells designed to be applied directly to the door or to the wall beside the door; and the invention consists in a spindle extending through the door or wall, as the case may be, provided with a pull upon the outside and a spring to return the spindle, in connection with the hammer, the axis of which is at right angles to the axis of the bell and spindle, so that the movement of the spindle imparts a corresponding rotative movement in a plane parallel to the axis of the bell to strike the bell-hammer, the operative mechanism all arranged within the circumference of the bell, as more fully hereinafter described.

A is the base, which should correspond to the outline of the bell, and is secured to the wall or door B, or wherever it may be desired to fix the bell. C is the spindle, which extends through the wall or door B, provided with a knob, D, or other pull, upon the opposite side, and must enter within the circum-

ference of the bell E, which is secured to an arm, F, extending from the base. A suitable spring, G, tends to draw and hold the spindle in its extreme inward position. H is the hammer, hung upon a pivot within the circumference of the bell, at right angles to the axis of the bell, and connected with the spindle C, so that by pulling the spindle a corresponding rotative movement in a plane parallel to the axis of the bell will be imparted to the hammer, causing it to strike the bell. In Fig. 1 this connection is made by the pinion I, so that the axis of the pinion will be the center of motion of the hammer, and the rotative movement of the hammer will be in a plane parallel with the axis of the bell. Instead of the toothed connection between the spindle and wheel I, it may be as in Fig. 2, an arm, I', in connection with the spindle C.

I claim as my invention—

In combination with the base A and bell E, the hammer H and spindle C, arranged within the circumference of said bell, the spindle and hammer having their axis at right angles to each other, and connected substantially as described, whereby the movement of the spindle parallel to the axis of the bell imparts a corresponding rotative movement to the hammer in a plane parallel to the axis of the bell, substantially as set forth.

WILLIAM E. SPARKS.
